UNITED STATES PATENT OFFICE

148,694

DESIGN FOR A ROADSIDE REFRESHMENT STAND

Frederic S. Grover, Brighton, N. Y., assignor to Richardson Corporation, Rochester, N. Y., a corporation of New York

Application August 28, 1946, Serial No. 132,931

Term of patent 14 years

(Cl. D13—1)

To all whom it may concern:

Be it known that I, Frederic S. Grover, a citizen of the United States of America, residing at Brighton, in the county of Monroe and State of New York, have invented a new, original, and ornamental Design for Roadside Refreshment Stand, of which the following is a specification, reference being had to the accompanying drawings, forming a part thereof.

In the drawings:

Fig. 1 is a perspective view of a roadside refreshment stand, showing my new design;

Fig. 2 is a view in side elevation;

Fig. 3 is a view in end elevation, and

Fig. 4 is a view in end elevation looking in the opposite direction to Fig. 3.

I claim:

The ornamental design for roadside refreshment stand, as shown.

FREDERIC S. GROVER.
